METHOD AND APPARATUS FOR ELECTRICALLY REPRODUCING SOUND VIBRATIONS

Richard O. Whitelegg, Hagerstown, Md.

Application March 7, 1939, Serial No. 269,359

7 Claims. (CL. 84—1.14)

My invention relates broadly to an improved apparatus for electrically reproducing sound vibrations and more particularly to apparatus for electrically reproducing sound developed in musical instruments of the wind or pipe type.

One of the objects of my invention is to provide a mechanical assembly for tone generators which may be readily associated with the pipes of an organ for electrically reproducing tones in a position remote from the pipes and remote from the console.

A further object of my invention is to provide a construction of tone generator for connection with the pipes of an organ or chimes or in association with vibratory reeds in a musical instrument by which electrical energy is generated in accordance with the vibrations generated by the musical instrument and the electrical energy amplified and impressed upon a sound reproducing system for electrically reproducing the sound in any position remote from the musical instrument.

Another object of my invention is to provide means for coupling a device for generating electrical energy to the pipes of an organ or chimes or to the tone cavity of a reed system for generating tones.

Still another object of my invention is to provide an electrical control system for coordinating the operation of the pipes of a musical instrument with electrical generators individual to each of the pipes for selectively generating electrical energy in accordance with the vibration of the pipes and reproducing the electrical energy in a position remote from the pipes.

A further object of my invention is to provide a construction of electrical generators which may be readily attached to the organ pipes of existing organ installations for increasing the useful range of the organ by providing means for electrically reproducing sound from the organ in locations remote from the organ pipes with a high degree of quality and timbre and with accurate reproduction of pitch of the reproduced tones.

Other and further objects of my invention reside in the arrangement of electrical control systems for coordinating the operation of the pipes of an organ with the operation of the electrical generators as set forth more fully in the specification hereinafter following by reference to the accompanying drawings, in which:

Figure 1 is a schematic side elevational view of the pipes and wind chest of a pipe organ equipped with the electrical generators of my invention;

Fig. 2 is a schematic plan view of the pipes and wind chest of a pipe organ illustrated in Fig. 1; Fig. 3 is an enlarged transverse sectional view with parts shown partially in side elevation taken in any representative position such as, for example, on line 3—3 of Figs. 1 and 2 and showing the arrangement of the electrical generators with respect to the organ pipes and an associated sound reproducing system connected with the electrical generators; Fig. 4 is a diagrammatic view showing the control circuit for an organ equipped with the electrical generator system of my invention and showing the coordination of the organ pipe controls and the electrical generators; Fig. 5 is a schematic view showing a modified form of my invention applied to chimes and illustrating the manner in which sound vibrations generated by the chimes may be electrically reproduced in a remote position; and Fig. 6 illustrates the application of my invention for electrically reproducing sound from a reed type instrument.

My invention is directed to an improved apparatus for electrically reproducing sound from vibratory pipes or reeds where it is desired to locally increase the amplitude of the sound or where it is desired to transmit electrical impulses corresponding to the sound to any remote position for reproduction at a distance. The apparatus of my invention permits the broadcasting of an organ recital by space or wired radio for the faithful and accurate reproduction of the original tones at a remote station. I provide selective tone generators which are responsive to the individual pipes of the organ for efficiently generating electrical energy in accordance with the vibration of the air column in that particular pipe. The electrical generator is designed to efficiently respond to the tone frequencies of its associated pipe and the electrical circuit with which each tone generator is associated is designed to efficiently transmit the generated range of frequencies. The amplification system through which the several electrical currents are transmitted is substantially uniform so that the wave form of the several tone generators may be uniformly amplified and transmitted through the amplification system and through a network to a transmission line for operation of a modulation circuit of a signal transmitter for broadcast over a wire line, or through a radio broadcast transmission system or directly to a sound reproducing system for electrically reproducing the tones generated by the several pipes. The system of my invention requires an electrical generator

efficiently responsive to the frequencies of the pipes of the organ which may vary from CCCC—32 feet, 16 cycles, to more than 40,000. The electrical generators are associated with the individual organ pipes, a partial list of the names and various stops of which are as follows:

Diapason group

16'	Diapason
10 10/3'	Quint
8'	Diapason
6 2/3'	Sub tierce
5 1/3'	Quint
4'	Octave
15 3 1/5'	Tierce
2'	Super octave
2 2/3'	Quint
1 1/3'	Tierce
1'	Fife

String group

16'	Violone
10 2/3'	Quint
8'	Gamba
25 6 2/3'	Sub tierce
5 1/3'	Quint
4'	Viol
3 1/3'	Tierce
2 2/3'	Quint
30 1 1/3'	Tierce
1'	Fife

Flute group

16'	Bourdon
10 2/3'	Quint Bourdon
8'	Bourdon
8'	Harmonic flute
6 2/3'	Sub tierce
5 1/3'	Quint
40 4'	Flute
3 1/3'	Tierce flute
2 2/3'	Quint flute
1 1/3'	Tierce flute
1'	Fife flute

Reed group

16'	Double trumpet reeds
8'	Trumpet reeds
8'	Oboe reeds
50 8'	Cornocean reeds
8'	English horn reeds
8'	French horn reeds
8'	Orchestral oboe reeds
8'	Vox humana reeds
55 8'	Clarinet reeds

Inasmuch as the electrical generators of my invention are designed to respond efficiently to the pipes with which they are associated and the electrical circuits connected with the generators 60 are designed to efficiently transmit the energy generated thereby, the electrical reproduction of sound follows faithfully the sound as originally produced by the organ pipes.

The system of my invention is superior to at 65 temps heretofore made in picking up organ recitals by variously positioned microphone circuits. Reproduction of pipe organ tones in a collective manner by either single or multiple microphones or other device have, up to the present 70 time been only partially successful. The average pipe organ covers a considerable cubic area which prevents a correct relative reproduction of tone frequency by a collective method, and due to many complex fundamental tone frequencies and 75 overtones, only an average tone or power can be

reproduced by a single pick-up device for the whole instrument. A performer at the console has to use special precaution to eliminate certain tone colours to avoid microphonic disturbances, and such tones as 16' Bourdons in many cases 5 fail to reproduce at all. Loud passages have to be damped to prevent further microphonic disturbances. My approach to the solution of the problem was to design a special means of conveying 10 the tone frequencies to a pick-up device without interference with the pipe resonator, which is designated as the portion of the pipe from the languid up to the extremity or node. A pipe resonator to function properly will not tolerate any interference by attachment of equipment, the 15 pipe resonator itself under power being a vibrant factor expanding and contracting as the column of air moves in its passage in a complex manner of tone frequencies, so the problem was to find a 20 means of conveying the tone frequencies to a pick-up device, suitable to its own frequency without in any way disturbing its own natural tone. The insertion of a tube in the languid has proven highly successful. All organ pipes sit loosely on what is termed the chest or sound-board supported in a vertical position by a rack-board, and each is supplied with wind at its lower extremity. By properly designing the organ pipes and inserting a tube in the languid passing 25 through the wind supply chamber to a position independent of the pipe, easily detachable and remote from interference from adjacent pipes, the electrical reproduction of sound from the organ pipes becomes highly practical. In such a 30 position in the languid of each pipe, the pick-up can only be very weakly affected by adjacent pipes and in any case the electromagnetic circuit is designed to remain open until a key closes the circuit, in which case the pick-up device functions as it is intended.

The electrical generators which generate the 35 electrical energy in response to the vibratory air column in the pipes are of the magnetic type and consist of a pair of magnetic pole members having windings thereon and wherein the pole members 40 are interconnected by horseshoe magnets formed from mixed quantities of iron, aluminum, nickel and cobalt having high and permanent magnetic properties. The permanent magnets which I employ in the electrical generators insure 45 the continued operation of the electrical generators over an indefinite period of time. The magnetic properties of the material I have selected for the permanent magnet systems in the 50 electrical generators are such that a permanent magnet formed from this material is capable of lifting 1250 times its own weight. The pole pieces are associated with a diaphragm which is disposed immediately above the pole pieces and peripherally suspended in a suitable manner. The 55 electrical generator is mounted with respect to a tube which extends into the organ pipe so that vibrations within the organ pipe are conveyed through the tube and directly impinge against the diaphragm. The sound vibrations from the 60 organ pipe change the physical position of the diaphragm with respect to the pole members and modulates the magnetic flux which threads the 65 windings about the pole members due to the intense magnetic field from the permanent magnet system. The modulations thus produced cause a 70 change in the current supplied to the input of the amplifier system when the electrical generator is selectively connected by operation of the 75 console to the amplifier system for electrically 76

transmitting a tone corresponding to the vibrations within the organ pipe.

Referring to the drawings in more detail, Figs. 1 and 2 schematically show a pipe organ having two rows of pipes extending vertically from the wind chest. I have designated the pipes as 1-34 and 70-97, inclusive. In the side elevational view of Fig. 1 I have shown the front row of the pipes 1, 3, 5, 7 and 9 with certain of the pipes illustrated partially in vertical section. The air under pressure from the fan blower is delivered through wind supply pipe 100 to the air chamber within the wind chest 101. Each of the organ pipes contains a tube 102 for conveying sound vibrations from the organ pipe to the electrical generator. The tube 102 is fixed in the languid of the pipe indicated at 103 and extends through the block 104 and is swaged therein as indicated at 105 forming an air-tight and shock-proof joint with the material of block 104. It is important that this juncture be absolutely airtight as the pressure from the air chest is delivered through the port 106 in block 105 and must be utilized in driving the organ pipe by passage through port 107 which concentrically surrounds the tube 102. The port 106 in block 104 registers with port 108 formed in the header 109 on the wind chest and leads to the port 110 extending into the air chamber 101 of the air chest. There are individual ports for the separate pipes, all leading to the air chamber of the wind chest 101. For purposes of explaining the invention I have shown the port 110 for serving pipe 9 and in the plan view in Fig. 2 I have shown port 111 serving pipe 10. In order to regulate the supply of wind to the pipes, separate valves are provided in the header 109 as indicated at 112, 113, etc. These valves are individually adjustable and control the supply of air from the air chamber of the wind chest 101 through ports 110, 108, 106 and 107 to the pipe 9 (for example). Each of the ports 110, 111, etc. admits air to the coextensive ports from the air chamber of the wind chest under control of a deflatable pneumatic pouch valve which I have indicated at 114. The pouch valve 114 is normally urged to a position closing the associated port 110 by spring 115. The deflatable pneumatic pouch is disposed immediately over an air chamber 116 connected through ports 117, 118 and 119 to the valve chamber 120 of the magnetically actuated valve 121 which is normally in communication with the wind chest 101 so that pneumatic pressure on both sides of the pouch valve 114 is equalized, as will be understood. The magnetically actuated valve 121 includes a pair of electromagnetic windings 122 wound on pole pieces 123 which control magnetic disc valve 124. A screen of metal 121a covers the electromagnets 122 with a port 121b therethrough communicating with the air chamber in the air chest 101 and by which air is led to the valve chamber 120. When windings 122 are energized, the pole pieces 123 are magnetized and attract disc valve 124, shutting off the air from the air chest 101 and opening port 125 which permits the exhausting of air from the air chamber 116 and the collapsing of the pouch valve 114 allowing air from the air chamber 101 to pass through port 110 to the organ pipe.

70 The electrical generators are mounted directly beneath block 104. As illustrated in Fig. 3, the generators each include a casing 126 screw threaded at the upper extremity thereof to receive a screw threaded cap 127 which serves to clamp in position the magnetic diaphragm 128

between annular gasket members 129 and 130. The gaskets 129 and 130 are formed from yieldable material such as superimposed layers of linen and cloth permitting control vibrations of the magnetic diaphragm 128. The casing 126 5 provides a housing for pole members 131 and 132 which are in the form of angles secured against the rear wall of the casing 126. The pole members 131 and 132 each carry magnetic windings 133 and 134 which are electrically connected in 10 series and which are connected to terminals 135 and 136 which are insulatingly supported with respect to the pole members 131 and 132 and with respect to the casing 126. A pair of horseshoe permanent magnets are mounted within casing 15 126 in magnetic circuit with pole members 131 and 132. Only one of these horseshoe magnets 137 is illustrated in the drawings as the complementary horseshoe magnet is in the forward port of the casing 126, not cut by the transverse section line. Suitable means for maintaining the permanent magnets in position are provided such as screw members 138 coating with the kidney pieces 139. The permanent magnets employed have high magnetic properties and are constructed 20 from an alloy of iron, aluminum, nickel and cobalt. The pole pieces 131 and 132 are spaced below the diaphragm 128 and immediately beneath the sound conveying tube 102 so that sound vibrations from the vibrating air column in the 30 organ pipe are directly conveyed through tube 102 for bombardment of the diaphragm 128. The gap bridged by the magnetic flux between the magnetic diaphragm 128 and the pole pieces 131 and 132 is varied in accordance with the 35 sound vibrations, thus changing the flux density threading the windings 133 and 134, and generating therein current impulses which are transmitted through the circuits 140 to the keying system designated generally at 141 in Fig. 3 and 40 thence through the amplifying system designated generally at 142 for operation of the sound reproducer indicated generally at 143. Thus it will be seen that mechanical vibrations established by vibrating air in the organ pipe impart movement to the diaphragm 128 effecting an electrical charge in the windings 133 and 134 which is amplified to operate an electrical sound reproducing system. Such system may be located in a remote position so that it is possible to faithfully 45 reproduce the organ recital at a point remote from the organ pipes. A listener within the area of the sound propagated by the organ will hear the program directly from the organ and yet in some remote locality the same program may be 50 electrically reproduced. The remoteness in the position of the reproducing device may be indefinite as the control circuits from the electrical generators may control the modulating circuit of a radio transmitter or a wired radio transmitter for effecting wide distribution of the organ 55 recital.

By way of illustration, I have indicated the various notes which are reproduced by the various pipes in Fig. 2.

In Fig. 4 which shows the control circuit for the organ and electrical sound reproducing system, I have illustrated one of the keying circuits controlled by key 144. The contact system 145 controls the circuits through the chest magnets 70 indicated generally at 121 while the contact system 146 controls the circuits through the electromagnetic windings 133 and 134 of the tone generators. I have shown one complete key with fifteen stop controls. A mixing transformer 147 75

having a primary winding 148 and a secondary winding 149 is provided between the keying circuit and the input to the amplifier 142. A high impedance coupling circuit is provided between 5 secondary winding 149 of the mixing transformer 147 as indicated at 150. The power supply to the amplifier system is furnished through leads indicated generally at 151. The mixing transformer has the primary winding thereof tapped 10 to resonate the input circuit of the amplifier at the frequency of the tone generator which is connected to the keying circuit. The circuits to the different tone generators which produce different notes extend from taps on primary winding 148 indicated at 0', 6', 8', 11', 15', 22', 30', 40', 52', 64', 15 79', 91', 118', 146' and 181'. The individual keying circuits are each provided with series connected resistors which I have indicated generally at 182. The power supply for the chest control 20 magnets is obtained from generator 153 with filter system 154 connected therewith as shown. The fact that an individual electrical generator is 25 functioned by each organ pipe enables the separately generated frequencies to be integrated in the input system of the amplifier for reproduction of sound with quality and timbre and pitch comparable to the originally generated sounds.

The two leads at 180 extending through individual resistors 152 to taps 0' and 6' on primary 30 winding 148 are required for the reason that these circuits independently control and operate at tones having different strengths. The two leads on the 16' circuit at 180 provide for soft register number one and two at a louder strength, 35 and similarly with the three leads on the 8' line indicated at 181, different amplitudes may be reproduced. These are musical interpretations of tone power. These tone strengths are obtained by using different ratings of resistors 152 in 40 series in the line, as indicated in Fig. 4.

The system of my invention may also be employed in chimes of the kind illustrated in Fig. 5. A tubular chime has been shown at 155 suspended through link 156 from support 157. The lower 45 end of the tubular chime 155 has a transversely extending central flange 158 thereon which is gripped by means of screw cap 127 which engages casing 126 and also supports magnetic diaphragm 128 in suspension between gaskets 129 and 130. 50 The parts of the electrical generator have been numbered similarly to the parts illustrated in Fig. 3. The connections from the generator to the electrical sound reproducer are similar to the connections illustrated in Fig. 4. The striking 55 mechanism for the chimes has been shown generally at 159, including a hammer 160 pivoted at 161 and having an armature 162 which is actuated by electromagnet 163 against the action of spring 164. The chime is struck when key 165 is operated 60 closing contactor 166 disposed in series with generator 167 and with the winding of relay 168. The contactor 169 of relay 168 is arranged in series with winding 163 of the actuator 159. The power to the magnetic actuating circuit is supplied 65 from the power source through leads 170.

In Fig. 6 I have shown a reed system in which tone generating reeds 171 are mounted adjacent a wind chamber 172. The air pipe to the wind chamber 172 is indicated at 173. A valve for the 70 reed indicated at 171 is illustrated at 174 normally pressed to closed position by means of spring 175. Control link 176 extends from the valve 174 through system of levers 177 to the control key 178. The electrical generator which is operated in accordance with the vibration of 75

the air column in the tone cavity 179 is mounted adjacent an aperture 180 in the wall of the tone cavity 179. The electrical generator has the screw cap 127 thereof apertured at 181, the said aperture registering with aperture 180 in 5 the wall of the tone cavity 179. The magnetic diaphragm 128 is mounted intermediate suitable annular gasket members 129 and 130, as heretofore explained, and adjacent the pole pieces 131 and 132 associated with the electromagnetic 10 windings 133 and 134 arranged in association with the permanent magnet system 137 within casing 126. The outputs of the several electromagnetic windings 134 and 133 of the electrical generators associated with the various reeds are 15 impressed upon the input of the amplification system 142 through coupling circuit 150 operating sound reproducing system 143.

The coordination of the individual pipes and the means for reproducing each pipe tone electronically, greatly increases the esthetic qualities and musical tone colour that can be expressed by a performer. Heretofore in simple organ mechanisms where coupler controls are used on individual ranks of pipes having a fixed tonal 20 power, severe limitations have been imposed on such coupler arrangements. However, by the coordination of the electromagnetic means of my invention, it is possible to accurately determine tone strength for such intervals as require either 25 fundamentals or partials adjusted to obtain imitative tone colours, by the inclusion of electrical resistors 152 in series in the electromagnetic circuits. The electromagnetic circuits are designed to enable a performer to obtain several 30 determined tonal strengths, for instance at 16' pitch two are provided as at 180 and again at 8' pitch three are provided as at 181, permitting a flexible arrangement for a performer, which is not possible with only a simple organ mechanism as applied to method of general organ 35 construction. In small instruments the coordination is invaluable, saving the necessity of specially constructed chambers, if it is not desired to hear the pipes which produce tone frequency 40 for transmission to a pick-up device. The elimination of several chambers can also be accomplished and the amplification system can be located at various positions, providing ample power, whereas without the coordination method of my 45 invention, it might be necessary to install many additional ranks of pipes. My invention is particularly applicable in meeting problems in large auditoriums, and in places normally unsuccessful for organ reproduction due to acoustical 50 conditions, absorption and loss of tone power and interference in sound travel, particularly where installations are provided with chambers distant from the console and having a time lag that is detrimental to the proper technical interpretation 55 of music by a performer. The coordination provided by my invention is an economy, while at the same time making possible a true reproduction of pipe organ tones.

It will be understood that the electrical generators may be secured in relation to the pipes or tone cavity in any suitable manner such as by means of detachable brackets by which the individual generators may be insulated or replaced. It will also be understood that in certain 70 instances it is desirable to mount the electrical generators adjacent the tube of a pipe or at one side of the pipe in a position to receive a portion of the pressure diverted from the pipe through a tubular member having its inlet disposed with- 75

in the pipe and its outlet extending to a position remote from the pipe for delivering pressure effects to the displaceable magnetic element of the electrical generator. The circuits leading from the electromagnetic windings of the various electrical generators may be tuned to resonance to the particular frequencies generated by the associated organ pipes or reeds so that musical impulses may be transmitted over the entire frequency spectrum efficiently for accurate reproduction in accordance with the original tones produced by the pipes or reeds. It will also be understood that various methods of coupling may be provided between the input of the amplifier and the electromagnetic windings of the electrical generators.

I have illustrated my invention in certain of its preferred embodiments, but I desire that it be understood that modifications may be made and that no limitations upon my invention are intended other than may be imposed by the scope of the appended claims.

What I claim as new and desire to secure by Letters Patent of the United States is as follows:

1. In combination with an organ chest having a multiplicity of pressure distributing ports extending therefrom, block members having ports therein aligned with the ports of the organ chest, organ pipes supported by said block members and provided with pressure passages connected with the ports in the block members, means for generating electrical energy associated with each of said pipes and depending from said block members, said means each including a magnetic member vibratile in the field of an electromagnetic winding, means for conducting vibrations from each of said pipes independently through said block members to the vibratile member in the respective generating means, the electromagnetic windings of each of said generating means being adapted for connection to sound reproducing means electrically reproducing tones corresponding to the tones generated by the respective pipes.

2. In combination with an organ chest having a multiplicity of pressure distributing ports extending therefrom, block members having ports therein aligned with the ports of the organ chest, organ pipes supported by said block members and provided with pressure passages connected with the ports in the block members, tubular members extending into each of said pipes and projecting through the pressure passages interconnecting the block members with said pipes and terminating exteriorly of said block members, and means for generating electrical energy mounted adjacent the exterior terminus of each of said tubular members, said means each including a magnetic member vibratile in the field of an electromagnetic winding and individually exposed through the respective tubular members to the sound vibrations generated by the respective pipes, the electromagnetic windings of each of said means being adapted for connection to sound reproducing means for electrically reproducing tones corresponding to the tones generated by the respective pipes.

3. In combination, an electromagnetic valve action for an organ pipe, an electrical generator individual to the organ pipe and operable for converting the sound vibrations thereof into electrical energy, individual electrical control means

connected with said valve action and with said generator, and actuating means for said control means operative in common with respect thereto for simultaneously energizing said electromagnetic valve action for sounding said pipe and connecting said generator for supplying electrical energy corresponding to the sound vibrations of said pipe.

4. In combination, an organ pipe for sustaining a tone frequency under the action of pneumatic pressure supplied to the pipe and having a languid transversely positioned at the lower end of said pipe, a tubular member concentrically disposed within said pipe and fixed in the languid of said pipe with an inlet opening into said pipe and an outlet extending below said languid and terminating remotely with respect to said pipe, and an electrical generator disposed adjacent the outlet of said tubular member and operative by pressure effects delivered through said tubular member from said pipe for generating electrical currents corresponding to the sustained tone frequency.

5. In a sound reproducing system, an organ pipe for sustaining a tone frequency under the action of pneumatic pressure supplied to the pipe, a languid in said pipe, a tubular member concentrically disposed within said pipe and fixed in said languid with an inlet opening into said pipe and an outlet extending coaxially from said pipe, and an electrical generator disposed adjacent the outlet of said tubular member and operative by pressure effects delivered through said tubular member from said pipe for generating electrical currents corresponding to the sustained tone frequency produced when said pipe is sounded.

6. In a sound reproducing system, an organ pipe for sustaining a tone frequency under the action of pneumatic pressure supplied to the pipe, a languid in said pipe, means for supporting said pipe, a tubular member extending into said pipe and fixed in said languid with an inlet opening into said pipe and an outlet extending through said supporting means and having an end portion enlarged in diameter for securing said tubular member in said supporting means, and an electrical generator disposed adjacent the enlarged outlet of said tubular member and operative by pressure effects delivered through said tubular member from said pipe for generating electrical currents corresponding to the sustained tone frequency produced when said pipe is sounded.

7. In combination with a wind chest having a multiplicity of pressure distributing ports extending therefrom, block members having ports therein aligned with the ports of the wind chest, sounding means supported by said block members and provided with pressure passages connected with the ports in the block members for producing tone frequencies under the action of pneumatic pressure selectively supplied to said sounding means from said wind chest, means for generating electrical energy associated with each of said sounding means and depending from said block members, said generating means each including a vibratile member, and means for conducting sound vibrations from each of said sounding means independently through said block members to the vibratile member in the respective generating means.

RICHARD O. WHITELEGG.
